[57] CLAIM

The ornamental design for a combined radio and tape player, as shown.

DESCRIPTION

FIG. 1 is a top, rear and left side isometric view of a combined radio and tape player showing my new design;

FIG. 2 is a top plan view thereof;

FIG. 3 is a front elevational view thereof;

FIG. 4 is a sectional view taken along line 4—4 of FIG. 3; and,

FIG. 5 is a reduced scale bottom plan view thereof. The right side of the combined radio and tap player is plane and unornamented.

FIG. 4
